Att'l. 715.

UNITED STATES PATENT OFFICE.

JARVIS M. ANDREWS, OF WOLLASTON, MASSACHUSETTS, ASSIGNOR, BY MESNE ASSIGNMENTS, TO TECHNICOLOR MOTION PICTURE CORPORATION, OF BOSTON, MASSACHUSETTS, A CORPORATION OF MAINE.

ETCHING APPARATUS FOR CINEMATOGRAPHIC FILMS.

Original application filed November 19, 1921, Serial No. 516,357. Divided and this application filed September 24, 1925. Serial No. 58,287.

This invention relates to a device for directing a stream of fluid against a cinematographic film and more particularly to an air nozzle for blowing the superficial liquid from a film as it is fed past the nozzle in a wet state. While the invention may be used in many processes where a film is fed from a wet stage to a drying stage, as from a washing stage to a drying stage, it is particularly applicable to an etching process such as disclosed in application Ser. No. 516,357, filed Nov. 19, 1921, now Patent No. 1,559,145, granted October 27, 1925, of which this is a division.

15 The invention consists in the improvements hereinafter claimed and illustrated in the accompanying drawings in which,—

Fig. 1 is an elevational view of the lower part of the device;

20 Fig. 1^a is a similar elevational view of the upper part of the device;

Fig. 2 is a section on line 2—2 of Fig. 1;

Fig. 3 is a section on line 3—3 of Fig. 2;

Fig. 4 is a section on line 4—4 of Fig. 2;

25 Fig. 5 is a section on the line 5—5 of Figure 6;

Fig. 6 is a section on line 6—6 of Fig. 2.

The particular embodiment of the invention chosen for the purpose of illustration is shown as applied to apparatus for continuously developing, bleaching and fixing cinematographic films. Such apparatus ordinarily comprises a series of tanks through which the film is continuously fed in succession. In Fig. 1 two such tanks are shown at 1 and 2, the others to the right being omitted. The film enters tank 1 over rollers 3, thence passes downwardly around roller 4, thence upwardly over roller 5, thence downwardly in tank 2 over roller 6, and thence upwardly to roller 7 where it passes to the left into a drying chamber or to other film-treating apparatus. According to the present invention the tank 1 may be a wash tank and tank 2 an etching tank, the latter tank being provided with an overflow 8 which communicates with the tank at the bottom and overflows at 9.

50 The liquid nozzle above referred to preferably comprises an orifice 10 located at the edge of the film so as to direct the liquid onto the film from the side. When the film is

double-coated and is to be etched on both sides, the orifice is preferably so positioned that it is bisected by the plane of the film, as shown in Fig. 5, whereby the liquid is directed to both sides of the film from the same orifice. In order to position the film relatively to the orifice, guides are provided adjacent the orifice and in the preferred embodiment illustrated in the drawings these guides are mounted upon and formed integrally with the nozzle, the guides being in the form of flanges 11 and 12 forming a channel 13 therebetween to receive the film. These flanges are preferably shaped and positioned to bear upon the film only at points 14 and 15, thereby to center the film relatively to the orifice without engaging the film throughout a very large area. The flanges 11 and 12 preferably extend only to the sprocket holes of the film, the position of which is indicated at 16 in Fig. 2 so as not to rub against the image-bearing portion of the film. By inclining the nozzle relative to the path of the film, as shown in Fig. 5, the ends of the flanges serve as the bearings for guiding the film and the orifices are inclined to the path of the film so that an adequate quantity of water is directed to both sides of the film even though the film is somewhat warped and therefore does not lie wholly in the plane defined by the bearing edges 14 and 15. In the particular embodiment illustrated, identical nozzles are provided on opposite sides of the film, and they connect through branched ducts 17 and 18 with a common supply pipe 19.

The nozzles 10 are preferably located directly above the etching tank 2 so that the film extends substantially vertically from the tank to the nozzles, especially if the film is to be etched on both sides. The distance of the nozzles above the tank depends upon the rate of liquid flow, its temperature, the rate of film travel, and the extent to which the etching progresses in the tank 2, but in any event the distance is sufficiently great so that the film is completely etched by the time it reaches the nozzles.

100 A suitable etching liquid comprises water at a temperature of about 120° F. the water being supplied at such a rate that a stream flows down each side of the film from the

nozzles to the tank 2, the stream being relatively thin or shallow but extending the full width of the film. With the rate of flow properly adjusted both sides of the film can be fully covered throughout the entire distance between the nozzle and the tank without any of the liquid overflowing at the edges of the film.

In the illustrated embodiment the film passes between opposed air nozzles 20 shortly after passing between the liquid nozzles 10. The preferred construction of the air nozzles comprises two tubular members extending in parallel relationship along opposite sides of the film, and joined at 21 with the two branches 22 of larger tube 23, the end of which is formed as shown in Figs. 2 and 4 to fit the ends of the tubes 20. On the inner side of the tubes 20 are longitudinal slots 24 facing the opposite sides of the film. Fitting within the tubes 20 with a snug sliding fit, are tubes 25 which are provided with narrow longitudinal slots 26. The tubes 25 are open at their lower ends (Fig. 2) and closed at their upper ends, the upper ends being provided with handles 27 which project beyond the open ends of the outer tubes 20. By means of handles 27 the inner tubes may be rotated to adjust the direction of slots 26, thereby to adjust the angularity of the jet of air from the nozzles to the film. Ordinarily the slots 26 are directed obliquely of the film contrary to the direction of film travel but good results and sometimes better results can be obtained by making the slots face the film perpendicularly or by inclining the slots slightly in the direction of film travel, the liquid being rolled downwardly at the line of intersection of the planes of the film and jet with less tendency to splash.

An improved feature of the invention involves the oblique arrangement of the air nozzles relatively to the film, the nozzles being oblique relatively to both the transverse and longitudinal dimensions of the film, the preferred degree of angularity being illustrated in Fig. 2. In addition to this oblique disposition of the tubes the slots 26 are preferably positioned by means of the handles 27 so that the air jets are directed downwardly and to the left (Fig. 2). With this arrangement substantially all of the superficial liquid is blown off the film and at the same time the streaks on the film, caused by prior air nozzles, are avoided. If the tubes 20 extended horizontally parallel to the transverse dimensions of the film so as to blow the water downwardly along the film, there would be a tendency for streaks longitudinally of the film to appear after the film is dry. If the air nozzles were located at one edge of the film to blow horizontally across the film, there would be a tendency toward unequal removal of the superficial liquid and in some cases a con-

siderable amount of the liquid might not be blown off, especially near the edge of the film opposite to the air nozzles.

The operation of the apparatus is as follows: The film is fed continuously through the apparatus as aforesaid. As the film passes through the tank 2, the gelatin to be etched away is softened and may be etched away to some extent, this tank being filled with water at approximately 120° F. As the film passes upwardly from the surface of the body of liquid in tank 2 to the nozzles 10, both sides of the film are subjected to the action of a rapidly flowing stream of hot water. This stream of water is naturally agitated by its own flow and is further agitated by the sprocket holes which tend to divert the water inwardly from both sides toward the center thereby keeping it thoroughly stirred. The result is that the soft gelatin is rapidly carried away and the film, after passing nozzles 10, is entirely cleansed of soft gelatin leaving the hard gelatin in sharp relief. Inasmuch as the marginal portions of the film are never exposed, the gelatin on the margins entirely washes away leaving perfectly clean celluloid outside the sprocket holes. After the film passes nozzles 10 it passes between nozzles 20 where the liquid superficially adhering to the film is blown off so that the film may be quickly dried when subsequently passed through a drying chamber. The tank 2 may be continuously replenished with hot water by a pipe opening thereinto either at the top or bottom or any intermediate position, but ordinarily the water flowing downwardly along the film from the nozzles 10 is sufficient for this purpose.

By virtue of the above-described method and apparatus, the film is etched rapidly and cleanly, and the amount of hot water required for the purpose is only a small fraction of the amount required by other known processes.

I claim:

1. In a cinematographic device, the combination of means for continuously advancing a film along a predetermined path, and an elongate nozzle extending approximately parallel to the film but obliquely to the path of the film, the outlet of the nozzle being adapted to be directed toward the film.

2. In a cinematographic device, the combination of means for continuously advancing a film along a predetermined path, and an elongate nozzle extending approximately parallel to the film but obliquely to the path of the film, the outlet of the nozzle being adapted to be directed in a direction transverse of the film and counter to the direction of film advance.

3. In a cinematographic device, the combination of means for continuously advancing a film along a predetermined path, and

an elongate nozzle extending along one side of the film, the outlet of the nozzle being angularly related to the film and being angularly adjustable relatively thereto.

5 4. In a cinematographic device, the combination of means for continuously advancing a film along a predetermined path, and a tubular nozzle extending along one side of the film, the nozzle having an outlet along 19 one side thereof and being rotatable to adjust the position of the outlet relatively to the film.

15 5. In a cinematographic device, the combination of means for continuously advancing the film along a predetermined path, and a tubular nozzle extending along one side of the film, the nozzle having a longitudinal slot along one side and being rotatable about its axis to adjust the angularity of the slot 20 relatively to the film.

6. In a cinematographic device, the combination of means for continuously advancing a film along a predetermined path, and an elongate nozzle extending along one side of the film, the nozzle comprising two telescoped tubes rotatable relative to each other, one tube having a wide slot along one side and the other tube having a narrower slot movable transversely of the wide slot upon relative rotation of the tubes. 25

7. A nozzle of the character described comprising two telescoped tubes rotatable relative to each other, one tube having a wide slot along one side and the other tube having a narrower slot movable transversely 30 of the wide slot upon relative rotation of the tubes. 35

Signed by me at Boston, Massachusetts,
this 22nd day of September, 1925.

JARVIS M. ANDREWS.
